ABSTRACT OF THE DISCLOSURE

A new support and displacement mechanism is provided for a wiper element such as a doctor blade whereby a uniform and self-compensating positioning of the element is achieved at all locations along its length. The blade is pivotally mounted, and correct spacing or position is provided by a tubular member mounted longitudinally along the rear portion of the blade. The walls of the tubular member are flexible, and largely inelastic, and the tube is filled to partial capacity with a non-compressible fluid such as a liquid or fluidized particles. Air or other compressible fluid is excluded from the tubular member. A complete doctor blade assembly is described.

This application is a continuation-in-part of copending application Ser. No. 719,413 filed Apr. 8, 1968 and now abandoned.

BACKGROUND OF INVENTION

The use of wiper elements such as doctor blades is well established in numerous arts such as the coating art, the paper making art, and the like. The doctor blade in these arts is positioned adjacent to a moving surface, and is brought into close proximity or in contact with the surface so as to regulate the thickness of a coating thereon, or to scrape or remove excess coating, foreign material or the like from the surface. In the paper making art, for example, a doctor is employed at various places to remove water from the surface of the roller and to maintain the substantial absence of foreign material on the surface. The doctor may be employed at any of the rotating rolls or drums as desired.

It is known that a pivotally mounted doctor blade can be brought to the desired position of adjustment with relationship to the moving surface with a minimum of difficulty. The adjustment mechanism for the blade may be a mechanical adjustment such as rotation, retraction, extension or the like, as desired. Recently, there has been employed a pneumatic adjustment through the use of an inflatable tube positioned against the rear surface of the blade, and adjustment is achieved by adjusting the gas pressure in the tube. A pneumatic adjustment has certain obvious advantages, but it also has certain disadvantages. For example, a pneumatic device requires relatively delicate adjustment, and is essentially equivalent to a spring member. While it is possible for the operator to adjust the air pressure in the tube, this in turn leads to further disadvantages if the operator has the opportunity and responsibility to maintain blade adjustment.

In addition, there are certain limitations in pneumatic adjustments, and for that matter, in any prior mounting system. In many situations, a doctor blade is required to operate in conjunction with a surface whose shape at the line of intersection varies with operating conditions or with the position of the blade element on the work surface. For example, calender rolls frequently operate under relatively high pressure, and are crowned so that there is self-compensating adjustment for the bending of the roller under pressure. This means that the shape of

2

a surface segment or line of intersection with a doctor blade changes from position to position around the roller, and also with machine speed, roller pressure and the like. To some extent, this can be compensated by machining the doctor back or support member for the blade holder and again there are limitations caused by the varying operating conditions.

DESCRIPTION OF INVENTION

According to the present invention, a number of the difficulties and limitations in prior art doctor blade mountings are overcome by positioning a pivotally or rotatably mounted doctor blade adjacent to the surface to be maintained, and controlling the position of the opposite portion of the blade by displacement against a yieldable member comprising a tube having a largely inelastic but yielding wall, filled to a fraction of its maximum capacity with a non-compressible fluid and excluding compressible material. The invention is illustrated in the following specification, and in the drawings in which:

FIG. 1 is an exploded view of a doctor blade assembly;

FIG. 2 is an end view in cross section of a doctor assembly;

FIG. 3 is an end view of a segment of a support member awaiting a sealing operation;

FIG. 4 is a view of a slotted blade according to one embodiment of the invention;

FIG. 5 is an end view in cross-section of another doctor assembly;

FIG. 5A is a cross-section of a part of the doctor assembly shown in FIG. 5 but taken in another plane parallel to the section of FIG. 5;

FIG. 6 is an isometric view of the support member of FIG. 5;

FIG. 6A is a fragmentary plan view of the support member; and

FIG. 7 illustrates the relationship of the blade and blade-retainer shown in FIG. 5.

In FIGS. 1 and 2 is shown one embodiment of a doctor blade assembly, generally designated 10, mounted on a support member 11. The support member 11 is suitably positioned on a machine or device utilizing a doctor mechanism for smoothing a coating, removing an excess of material or the like. Such machine may, for example, be a paper machine and it is understood that the doctor blade assembly 10 illustrated in FIGS. 1 and 2 is well adapted for the rolls requiring doctoring in a paper machine, and in textile machines and the like.

A frame member 12 of the blade assembly is secured to the support member 11 by conventional means such as a bolt 14. Either the support member itself, or the positioning of frame member 12 on the support member 11 is adjustable, as is conventional, to achieve proper action

between the doctor blade and a work surface. Frame member 12 along its front end has a jaw 15 characterized by being a smooth edged, extremely flat surface thus forming a uniform supporting pivot for a doctor blade 16 which is removably positioned in the blade assembly.

A lower jaw 17 is mounted on the frame member 12, by suitable means. For example, a spacer bar 19 and plate 20 may be secured by rivets 21, holding the lower jaw member 17 parallel with frame member 12, with the lip 22 thereof defining an opening or mouth along the length of the blade assembly. As shown in FIG. 2, the mouth defined by upper and lower jaws 15 and 17 is adapted to receive a removable doctor blade 16 with or without a support plate 24.

In the embodiment of the invention illustrated in FIGS. 1 and 2, a support plate 24 is removably positionable in the jaws 15 and 17, being relatively loosely held in the jaws. Desirably, upper jaw 15 is rigid defining an im-

movable pivot for blade 16, and lower jaw 17 is relatively flexible, causing it to press lightly against support plate 24. The support plate 24 is a thin blade-like member, preferably of metal and desirably of a non-corrosive material such as stainless steel, with an end section or guard 25 bent downward over the edge of the blade assembly, effectively positioning the assembly in a longitudinal direction. Dimples 18 in the blade retain it in the assembly.

Positioned along and within the mouth of the blade assembly is a flexible support member 26 held loosely in position by retainers 27, the flexible support member 26 being positioned to support the blade 16 behind the pivot position of upper jaw 15, flexibly holding the blade at a desired rotational position within the doctor blade assembly as will be further described herein. The blade is removably secured in the assembly along the upper surface of support plate 24, the pressures of jaws 15 and 17 being sufficient to secure blade 16 in position while allowing it to be removed manually when desired. When blade 16 is removed, support plate 24 is loosely held by the jaws, and dimples 29 are positioned to prevent plate 24 from being removed by gravity or by an accidental bang.

The support member 26 is shown more fully in FIG. 3. This member comprises an elongated, hollow, flexible body having a lower wall or base 30, adapted to rest on and be supported by plate 28 (see FIG. 2). An upper wall 31 preferably has a smoothly rounded or crowned upper surface and its center is thicker than the edges. The upper wall is adapted to yieldably support the support plate 24, and doctor blade 16, or if desired, directly support the doctor blade. A normally flat slit or central opening 32 runs lengthwise through the support member 26, causing it to resemble a partially flattened hollow tube. Along the edges of slit 32 may be located edge holes 33 adapted to receive plugs 34. The walls of the support member 26 are a flexible and desirably relatively inelastic material such as plastic or a heavy rubber or the like. In the normal conditions of operation, the member is essentially unstretched, and thus operatively its walls are not subject to significant stretching forces.

For use and operation, support member 26 is sealed at one end by applying a suitable cement to its inner surfaces, plugs 34 are inserted into the edges and the assembly pressed together and, if desired, heated to cause an end seal. The member is then filled with a suitable non-compressible fluid, as for example by holding it in a vertical or inclined position and pouring a fluid into its open end. The fluid is inserted in the absence of substantial pressure until the member is completely full, to the exclusion of air, with no more than minimal pressure. The inner edges of the orifice are thoroughly cleaned. Cement is then painted inside the open end of the member, another pair of plugs 34 inserted, and the end pressed to seal the member in a condition full of non-compressible fluid.

If the full benefits of the invention are to be enjoyed, it is important to avoid filling the member 26 to its full capacity under pressure sufficient to cause substantial elasticity of the walls of the member, because pressure filling can produce a situation in which some of the characteristics of a pneumatic pressure member are created.

The non-compressible fluid may be any suitable liquid such as water, oil, glycerine or other conventional hydraulic fluid. If desired, it may be a flowable solid such as, for example, finely divided solid particles which, particularly if substantially spherical in shape, will flow within the support member. It is desired that the non-compressible fluid act as a hydraulic fluid, such as a liquid, to transmit force uniformly along the length of the member. A solid material possessing the property known as plastic flow may also be used, with or without confining walls, provided hydraulic force is conveyed by such material.

In the doctor blade assembly as illustrated in the drawings, the blade is supported behind its axis of rotation against a displaceable material in the form of a tube of yieldable walls partly filled with a non-compressible fluid such as preferably water or other liquid. As illustrated, the tube lies in a relatively flat position and configuration so as to support the rotatably mounted blade firmly and yet yieldably. As is apparent, the pressure against the rear portion of the blade is uniform at all positions, and the blade, nonetheless, is held firmly and yieldably with a relatively small degree of movability. The control of the blade position or rotation is extremely accurate, and the incompressibility of the supporting fluid prevents gross movement of the blade position in response to varying temperatures of operating conditions, or in response to localized pressure, or displacement at the operating edge of the doctor blade.

By considering the forces acting on the blade and on the support member, one can see that the blade is able to act as if it consists of a number of independent segments. For example, if the operating edge of the blade is raised at one point along its length by non-uniformity of the surface against which the blade operates, the rear or supported edge of the blade is correspondingly depressed. This action displaces the non-compressible fluid away from the point of depression and causes the blade at all points to be held against the operating surface by equal force, thus causing the remaining length of the blade to be urged to rotate against a localized force. In this manner, the blade mounting is automatically self-compensating. If the blade is operated against a crowned surface, the act of elevating the central portion of the doctor blade automatically depresses the ends. This permits the blade to have added compatibility with curved surfaces or with surfaces of changing configuration. It also permits the blade to adjust to localized foreign material on the surface without producing equal adjustment along the entire length of the blade.

In FIG. 4, is illustrated one embodiment of a slotted blade suitable for certain applications and uses of doctor blades and adapted to maximize the flexibility and control imparted to blade assemblies by the displacement mounting as disclosed herein. For many uses and operations of this invention, the doctor blade 16 is a flat sheet of metal, plastic, laminated material or the like, generally rectangular in shape and having a straight operating edge. It should be relatively flexible to permit operation without jamming and should be constructed or selected according to the usual skill in the art. However, in some instances, the embodiment of FIG. 4 is preferred. According to this embodiment, the rear or supporting portion 36 of the blade member 16 is slotted or divided into segments so that the independent action of the blade is increased. The front or operating edge 37 of the blade is uniform to conform with the work surface. Terminal holes 38 at the end of each slot 39 increase the flexibility of segments 40 and prevent slots 39 from tearing during operation or handling. The blade has increased ability to turn or bend as pressures are applied against its operating edge. The resistance of the blade to a twisting action is highly dependent on the width of the blade member, and the slotted structure simulates a narrower blade while permitting the same control and support as is achieved with a wide blade. As is apparent, one blade segment can be depressed into the area of the support tube with a minimum of distorting force being carried through the adjacent segments. At the same time, however, the depression of one or several segments into the supporting tube creates its self-compensating displacement of the non-compressible fluid, and the consequent adjustment in the opposite direction to the remaining segments.

The liquid or non-compressible fluid should be chosen so that it is safe and is compatible with the conditions of operation. It should be non-reactive with the material of the walls of the tube. It should neither boil nor freeze

at operating temperatures, and should have a moderate thermal expansion coefficient. It should have a relatively high flash point, and should be non-toxic.

The blade assembly, support mechanism and other features of the invention are useful and applicable in virtually any place where a surface is to be wiped, cleaned, scraped, doctored or the like. This includes the paper making and textile arts, and also includes other uses that applications as are apparent from the description of the invention.

FIG. 5 shows another embodiment of the invention. Parts which are the same in FIGS. 2 and 5 have the same reference character. Parts in FIG. 5 which have the same function as parts in FIG. 2, but are different in structure, have the same reference character primed. Thus, the upper jaw 15 is the same in both, but the lower jaw 17' in FIG. 5 is made integral with the support member 26', which incorporates several other parts that are separate in FIG. 2, as appears in FIG. 6. The lower wall 30' of the support member extends to one side of the opening 32' to become the lower jaw 17' and lip 22' of the assembly, and a retainer rib 40 is formed integrally within the lip 22' for engaging the dimples 29' (which are more pronounced than dimples 29 in FIG. 2) to hold plate 24 against accidental removal. The lower wall 30' extends also to the other side of the opening 32' to provide a locking rib 41 for engagement between plate 20 and spacer bar 19' which is notched at 42 (FIG. 5A) to engage the rib 41. The edge along which the locking rib runs is cut out at selected locations 42, 43, etc. corresponding to locations of the rivets 21, as shown in FIG. 6A and 5. FIG. 5A is a section taken on a plane between the rivets, for example.

The support member 26' may be made of the same material as member 26. The upper wall 31' is flat, rather than crowned, to provide a larger surface bearing on the underside of the blade 16, if desired. The thinnest sections of the walls around the opening 32' are at the "shoulders" 44, 45 at each lower edge of the upper wall 31'. For sealing purposes, the ends of the support member 26' can be trimmed so that a tube having walls uniformly of this thickness extends beyond each end of the support member 26', and these ends can be sealed with a suitable cement and/or mechanically clamped shut, if desired. The thicker sections will be relatively stiffer, and in particular the jaw 17' can be made thick enough beyond plate 20 to be as firm and flexible as jaw 17 in FIG. 2.

FIGS. 5 and 7 show another structure for retaining blades in the assembly. The upper jaw 15 is fitted with a blade-locking strip 51, which is attached as by rivets 52 to the jaw near but within the lip edge of the jaw and bent on a line 53 parallel to the lip so that the strip projects from the jaw toward the upper rear surface of the blade, and the rear edge 54 of the strip can bear on the blade. Notches 55 may be provided in this rear edge, for a purpose to be described.

Blade-retainer clips 61 are fitted to the upper surface of the blade 16, near its rear edge as better shown in FIG. 7. These clips may be made of flat stock, bent over to provide a hook to engage the locking strip 51, and they may be riveted or otherwise attached to the blade 16. When made in the form shown, the notches 55 enable the blade to be inserted and removed through the lips of the jaws when the clips and notches are aligned as shown in FIG. 7. The blade is locked by moving it length-wise of the jaws, to engage the clips over the edge 54 of the locking strip, for which purpose a tool may be engaged in the hole 62 at the end of the blade. The blade may be inserted and removed endwise, in which case the notches 55 will not be required. The clips 61 are exemplary only; other forms of retainers, such as studs cemented, welded or riveted to the blade, may be used.

We claim:

1. A doctor blade assembly comprising a frame mem-

ber adapted to be positioned adjacent a work surface, a rotatably mounted doctor blade mounted to be supported by said frame member and pivoted around an axis along its length, yieldable displacement means positioned to limit rotation of said blade and consequently adapted to retain said blade in operating position against an adjacent work surface, said yieldable displacement means comprising a tubular member having at least one flexible wall positioned to bear against said blade and containing a fixed volume of non-compressible fluid to the exclusion of compressible material, the material of said wall being relatively inelastic such that in the range of normal conditions of operation it is substantially unstretched, whereby substantially uniform force is brought to bear against said blade element along its length.

2. An assembly according to claim 1 in which said frame member includes a first jaw member having an edge on which said blade bears at one side along said axis, a second jaw member flexibly bearing on the other side of said blade in a line further removed from said tubular member than said axis, and spacer means holding said jaw members apart on said frame member.

3. An assembly according to claim 2 in which said tubular member is incorporated with a base part integrally including means to attach said base part to said spacer means and an extension forming said second jaw member.

4. In an assembly for holding a blade element against a work surface, an elongated yieldable blade element supported in said assembly to bear against said work surface, yieldable displacement means supported in said assembly to receive through said blade element reaction pressure from said work surface, said yieldable displacement means comprising a tubular member disjoined parallel to said blade element and having at least one flexible wall positioned to bear against said pressure and containing a fixed volume of non-compressible fluid to the substantial exclusion of compressible material, the material of said wall being relatively inelastic such that in the range of normal conditions of operation it is substantially unstretched, whereby substantially uniform force is brought to bear against said blade element along its length.

5. A blade holder adapted to position a blade to bear against a work surface with substantially uniform pressure along its entire length comprising:

a blade member shaped to conform with a work surface; and

yieldable displacement means positioned and adapted to bear uniformly against said blade, said yieldable displacement means comprising a tubular member having at least one flexible wall positioned to bear against said blade and containing a fixed volume of non-compressible fluid to the substantial exclusion of compressible material, the material of said wall being relatively inelastic such that in the range of normal conditions of operation it is substantially unstretched.

6. The assembly according to claim 5 wherein the non-compressible fluid is a liquid.

7. A yieldable displacement member adapted for a blade assembly, comprising a tubular member having a base wall adapted to be positioned on a support surface capable of undergoing motion relative to a work surface, at least one flexible wall adapted to be positioned to bear against a blade member, said tubular member being sealed and filled with fixed volume of non-compressible fluid to the exclusion of compressible material, the material of said wall being relatively inelastic such that in the range of normal conditions of operation it is substantially unstretched.

8. A yieldable displacement member for a doctor blade assembly including a doctor blade and a support member therefor, said displacement member comprising: a longitudinally hollow tubular member having a base wall adapted to be positioned on said support mem-

ber and to be supported along its length by said support member; and, at least one flexible wall adapted to be positioned to bear against said doctor blade, said displacement member being sealed and substantially filled with a fixed volume of liquid to the exclusion of air, the material of said tubular member being relatively inelastic such that in the range of normal conditions of operation it is substantially unstretched.

9. A displacement member according to claim 8 having a part which extends from said base wall to provide an additional support member for a doctor blade.

10. A displacement member according to claim 9 having another part extending from said base wall opposite

to said first-named part for attachment to said support member.
